UNITED STATES PATENT OFFICE.

WALTER H. WAKEFIELD, OF WORCESTER, MASSACHUSETTS, ASSIGNEE TO CROMPTON & KNOWLES LOOM WORKS, OF WORCESTER, MASSACHUSETTS, A CORPORATION OF MASSACHUSETTS.

BOBBIN ANTIROLLING REPLENISHING MECHANISM.

Application filed December 29, 1923. Serial No. 683,389.

To all whom it may concern:

Be it known that I, WALTER H. WAKEFIELD, a citizen of the United States, residing at Worcester, in the county of Worcester and State of Massachusetts, have invented a new and useful Bobbin Antirolling Replenishing Mechanism, of which the following is a specification.

This invention relates to multi-color weft replenishing mechanism and more particularly to means for preventing the rolling of the bobbins due to the vibration of the loom as the latter is in operation.

In the type of replenishing mechanism shown in Patent No. 1,030,748, the bobbins are arranged in stacks, one stack for each color, and lie in substantially vertical guideways at the lower end of which are provided cradles or other devices for delivering one bobbin at a time to transfer position. The ends of the yarn on the spare bobbins extend to the thread holder at one side of the replenishing mechanism and when the yarn is fine the bobbins remain in the stacks for a considerable length of time, during which the ends extending to the thread holder become entangled. This condition is brought about largely by the rolling or rotation of the bobbins on their own axes due to the vibration of the replenishing mechanism as the loom operates.

An effort to prevent this rolling was made in a replenishing mechanism made according to an application filed May 27, 1922, bearing Serial No. 564,187, wherein the vertical guideways are composed of a series of short angularly disposed runs, each run accommodating but one bobbin. With such an arrangement it has been found that as the bobbins move downwardly they rotate in a manner similar to meshing gears, alternate bobbins moving in the same direction down their associated inclined runs while the intervening bobbins move oppositely and are given an opposite rotation.

It is the object of my present invention to utilize the general principle disclosed in said application but to arrange the bobbins and angular runs in such a way that all rotation of the bobbins will be prevented.

Accordingly I have constructed the short angularly disposed runs of sufficient length to take at least two bobbins so that as a number of bobbins having frictional con-

tact with each other move down each run the tendency to rotate in the same direction will be prevented by their frictional contact, the result of which is that the bobbins will move down the guideway without rotating on their own axes.

With this general object in view, my invention resides in the combination and arrangement of parts hereinafter set forth and claimed.

In the drawings wherein two forms of my invention are disclosed,

Fig. 1 is an end elevation of an inner portion of a weft replenishing mechanism with the bobbins shown in dotted lines,

Fig. 2 is a vertical section taken along the line 2—2 of Fig. 1, and

Fig. 3 is a fragmentary view similar to Fig. 1 but showing the bobbins arranged in a different manner.

Referring to the drawings, it will be seen that the magazine is provided with a stand 10 formed as part of a foot 11 which may be attached in any way to the loom side. A frame 12 is preferably formed as part of the stand 10 and is provided with a plurality of substantially vertical guideways 13, 14, 15 and 16, defined between ribs 17, 18, 19, 20 and 21, formed as part of the frame 12 and projecting laterally therefrom. In the lower portion of each guideway provision is made for cradles or other bobbin controlling devices 22, indicated more particularly in Fig. 2 as having slots 23 and 24 which may be made as shown in Patent No. 1,005,321, issued October 10, 1911. While this particular form of bobbin control is shown, yet it is to be understood that any form of control may be employed such, for instance, as that shown in the patent to Wyman No. 941,179.

My invention relates more particularly to the formation of the guideways and it will be seen from Fig. 1 that each guideway is provided with a series of relatively short runs angularly disposed with respect to each other. The runs 24 and 25 are shown as extending downwardly to the left while the runs 26 and 27 connected therewith are shown as running downwardly to the right. These runs are made of sufficient length to accommodate at least two bobbins.

In the operation of the replenishing mechanism when a weft change is about to oc-

cur, the slots 23 and 24 undergo a relative motion, the result of which is to open the cradle for the reception of the lowest bobbin in the associated stack. When this occurs, 5 the bobbins will move down the guideway in which they are contained and because of the fact that each run accommodates a pair of bobbins which are held in contact with each other by the weight of the superimposed bobbins, it is apparent that any tendency to 10 rotate because of movement down an inclined surface will be counteracted. When the bobbins are arranged as shown herein, it has been found that the uppermost bobbin will 15 move to the bottom of the guideway without undergoing any appreciable rotation. In providing an even number of bobbins for each of the angular runs, the tendency of half the bobbins to rotate in a right hand 20 direction under influence of the incline will be counteracted by the opposite tendency of the other bobbins to rotate in the same direction, the frictional contact of the bobbins preventing rotation.

25 In Fig. 1 I have shown the bobbins so disposed that a bobbin is located in each angle of the guideway but it is possible to have the guideways so arranged with respect to the cradles that the bobbins will be arranged as shown in Fig. 3 wherein the bobbins are located in that portion of the run intermediate the angles of the guideways.

Having thus described my invention, it will be evident that changes and modifica-

tions may be made by those skilled in the 35 art without departing from the spirit and scope of the invention as set forth in the appended claims, and I do not wish to be otherwise limited to the details herein disclosed.

40 What I claim is:

1. In a weft replenishing mechanism, a 45 guide-way adapted to receive a stack of bobbins therein, means to lower said stack of bobbins progressively in said guide-way, said 50 guide-way being made of a plurality of alternately inclined connecting runs and each run being of sufficient length to accommodate a plurality of bobbins.

2. In a weft replenishing mechanism, a 55 guide-way adapted to receive a stack of bobbins therein, means to lower said stack of bobbins progressively in said guide-way, said 60 guide-way being made of a plurality of alternately inclined connected runs and each run being of sufficient length to accommodate an even number of bobbins.

3. In a weft replenishing mechanism, a 65 guide-way adapted to receive a stack of bobbins therein, means to lower said stack of bobbins progressively in said guide-way, said 70 guide-way being made of a plurality of alternately inclined connected runs and each run being of sufficient length to accommodate a pair of bobbins.

In testimony whereof I have hereunto affixed my signature.

WALTER H. WAKEFIELD.
